(57) **CLAIM**

The ornamental design for a washing machine with cloth dryer, as shown and described.

DESCRIPTION

Washing machine with cloth dryer

1.1 is a front view of a first washing machine with cloth dryer;

1.2 is a back view thereof;

1.3 is a left view thereof;

1.4 is a right view thereof;

1.5 is a top view thereof;

1.6 to 1.8 are three perspective views thereof;

2.1 is a front view of a second washing machine with cloth dryer;

2.2 is a back view thereof;

2.3 is a left view thereof;

2.4 is a right view thereof;

2.5 is a top view thereof; and

2.6 to 2.8 are three perspective views thereof.

The broken lines in FIGS. 1.1, 1.2, 1.7 and 1.8 are for the purpose of illustrating portions of the washing machine with cloth dryer and form no part of the claimed design.

(Continued)

The portions shown in the color black in FIGS. 2.2, 2.7 and 2.8 are for the purpose of illustrating portions of the washing machine with cloth dryer and form no part of the claimed design.

1 Claim, 16 Drawing Sheets
